[57] CLAIM

The ornamental design for a message light, as shown and described.

DESCRIPTION

FIG. 1 is a right front perspective view of a message light showing our new design;

FIG. 2 is a right rear perspective view thereof;

FIG. 3 is a front elevation view thereof;

FIG. 4 is a right side elevation view thereof, the left side being a mirror image thereof;

FIG. 5 is a rear elevation view thereof;

FIG. 6 is a top plan view thereof;

FIG. 7 is a bottom plan view thereof;

FIG. 8 is a right front perspective view of a second embodiment of FIG. 1;

FIG. 9 is a right rear perspective view of the embodiment of FIG. 8;

FIG. 10 is a front elevation view of FIG. 8;

FIG. 11 is a right side elevation view of FIG. 8, the left side being a mirror image;

FIG. 12 is a rear elevation of FIG. 8;

FIG. 13 is a top plan view of FIG. 8;

FIG. 14 is a bottom plan view of FIG. 8; and,

FIG. 15 is a right front perspective view of a third embodiment of FIG. 1, having all other descriptive elements as FIG. 1.

The phantom line showing of a hand, lamps and lens are for illustrative purposes and do not form a part of the claimed design.
